UNITED STATES PATENT OFFICE.

CHARLES H. BATCHELDER, OF NORTH ATTLEBORO, MASSACHUSETTS.

CLASP FOR BRACELETS OR THE LIKE.

Application filed February 8, 1927. Serial No. 168,776.

My invention is a novel "click" or clasp for chain bracelets, necklaces or the like; also a novel spring for use in such a clasp; also a detent element for such a clasp, in which the parts may be assembled without riveting or solder, and retained securely in their several designed positions.

In the drawings:

- 10 Figure 1 is a perspective view of a clasp;
- Figure 2 is a plan view of a clasp;
- Figure 3 is a plan view of the detent element of a clasp;
- Figure 4 is a side view of the hook element of Figure 2;
- 15 Figure 5 is a plan view, on an enlarged scale, of the detent element shown in Figure 3, the top plate being removed and the aperture dotted in;
- Figure 6 is a section on line 6—6 of Figure 5;

Figure 7 is a perspective detail on an enlarged scale of the spring shown in Figure 5;

Figure 8 is a perspective view on an enlarged scale of the detent, showing the body, tang and finger piece;

Figure 9 is a side view of Figure 3.

The connection of the ends of chain or flexible bracelets and necklaces has hitherto been a source of some trouble to the user, the click or clasp being relatively light and unstable, so that the wearer, in securing the two parts of the clasp of a bracelet, for example, passed about the wrist, could not easily, with one hand, bring the two parts of the "click" into locked engagement. A common form of click or clasp as heretofore used was a bolt on one end of the chain extending in the direction of the length of the chain, which entered an aperture in the end of the opposed member of the "click" or clasp and was then in some manner engaged. The engagement of the two parts of the clasp was more or less difficult, owing to the fact that the opposed member was free to move and did move usually, during the attempt to enter the bolt into the other member of the clasp, frequently causing the free end of the bracelet to slip off the wrist. The same result occurred in cases where the engaging element was inserted into the opposed element from the side or sides.

It is an object of my invention to provide a clasp in which the force of the entry of the engaging half of the clasp is utilized to

steady and hold the other half of the clasp from movement.

It is an object also to provide a novel flat wire spring which will retain its integrity indefinitely, having no loops or other marked distortions tending to weaken the wire.

It is an object also to provide a novel "click" assembly by which the engaging jaw of the click may be movably mounted within a casing and secured against escape therefrom, without solder or riveting in a very cheap and efficient fashion.

In a chain bracelet or necklace, each link has upon the outer surface an ornamental face, the under part of each link having a box-like frame portion, giving a certain thickness to the link. In my new clasp or click one end member or clasp element is made up of an ordinary link, to one end of which, and extending longitudinally of the chain, is secured a link face plate, carrying upon its under surface, adjacent the free end thereof, a depending hook. The opposed member of the clasp is in effect a box link, without any face plate. In the upper surface of this member is an aperture, in size and shape adapted to pass the hook upon the other member. Within the inner space of the clasp element is mounted a spring pressed detent member, which, when the hook is passed through the aperture is pressed back to permit it to enter and then springs forward behind the hooked end and holds it in place.

The details of construction of the hook element and of the detent element are specifically new and are of importance in producing a successful and useful clasp and will now be described.

The hook clasp element is made up of a double link, one end 1 being the ordinary link of the particular chain and the other end 2, being the face plate of an ordinary link. The part 2 carries a hook 3 preferably shaped substantially as shown in the drawings (see Figure 4) the back of the hook being tapered off to form a wedge and having at the upper side a flat portion 4 to engage one edge of the aperture in the other clasp element. The wedge portion of the hook 3 is employed to wedge back the spring pressed detent 9, when the hook 3 is passed into the opposed clasp element through an aperture 8 in clasp 7, the tapered surface of the hook cooperating with the opposed

tapered surface of detent 9 within clasp 7 (see Fig. 6) to effect an easy movement and engagement of the parts. The flat part 4 of the back of hook 3, when the clasp is connected, cooperates with the opposed edge of aperture 8 to prevent any longitudinal relative movement of the two parts of the clasp. The hook 3 carries at its free end a detent engaging ridge 6. The other element 7 of the clasp is a frame or box-like structure, having, in its upper wall the aperture 8 and, within the box, the detent 9 and spring 10. The detent 9 is preferably shaped as indicated in Figure 8, and has a tang 11 at one end of the body 9 and a finger piece 12 at the other end of the body 9. In the sides of the frame 7 is a slot 14 and an aperture 15. The detent 9 is passed through slot 14 and the tank 11 is inserted in aperture 15, the finger piece 12 remaining on the outside of the box 7. The slot 14 has a wide part and a narrow part, the detent being passed through the wide part and the finger piece 12 then moved along the narrow part of the slot, against the resistance of spring 10. A small projection 16 on frame 7 is then bent down behind the finger piece, so that it cannot return to the wide part of slot 14. It will now be clear that, the body 9 of the detent being too wide to pass through the narrow portion of the slot 14, the detent 9 will be incapable of longitudinal movement, but capable of a limited transverse movement, against the force of spring 10, pivoting on tang 11 seated in aperture 15. This method of making and organizing the detent with the frame or box is very simple, very cheap and very durable and efficient. It requires no rivet, nor solder. It can be effected by unskilled labor. At one side of the detent 9, within the frame-box 7 is a spring 10 of zig-zag shape, preferably of bronze material, which does not rust and, due to its novel shape the spring does not break in service. This zig-zag flat spring lying all in one plane is a preferred and important element of my device, since it is desirable in such a part as the clasp element to limit its thickness while providing an easily flexible and a resilient spring, which requires a spring of some length, making for flexibility and distributing the strains of distortion so that there are no points in its length where the metal is or has been put under undue stress. This spring 10 is formed of a length of tempered wire, bent in a series of U shaped bends to form several sections lying in one plane.

The operation is as follows: The bracelet (for example), is placed about the wrist,

the clasp element 7 being laid with the aperture 8 upward. The other end 2 of the bracelet is then carried over the element 7 (see Figures 2 and 3) and the hook member 3 is passed into the aperture 8 and pressed down, forcing detent 9 to one side against the resistance of the zig-zag spring 10, until the ridge 6 on hook 3 passes the detent, which is immediately forced in behind ridge 6 by the zig-zag spring 10. It will be obvious that in this action no horizontal or transverse force is applied to the member 7 lying upon the wrist, tending to displace it or overcome its inertia. It will also be noticed that the moment the narrow free end of hook 3 is passed slightly into the aperture 8 the part 7 is in effect engaged and cannot slip or slide in any detrimental manner, because it will be caught by the hook 3 engaging the edge of aperture 8. Finally, it will be observed that the pressure necessary to spring the detent is resisted by the wrist, since the push is down. The disengagement is effected by operating the finger piece 12 to disengage the detent 9 from the hook 3 and lifting off plate 2.

I have indicated in the drawings, a part 17 for connecting a link with an adjacent link.

I claim:

1. In a chain bracelet or neck chain, or the like, a clasp made up of cooperating end members, one member made up of a face plate of another, from which face plate a hook depends, the said other member comprising a box element having an opening in its upper outer wall to receive the hook and means to detachably secure the hook against accidental return movement of the hook.

2. In a chain bracelet or neck chain, or the like, a detent clasp element, having side walls, a slot of two widths in one side wall and a flexible integral projection upon the wall adjacent the wide and narrow portions of the slot, a perforation in the other side wall opposite the slot; a spring pressed detent having a relatively thick body portion, a shouldered tang at one end and a relatively thin finger piece at the opposite end, the body portion passing through the enlarged portion of the slot to seat the tang in the perforation, the finger piece passing along the narrow portion of the slot and the integral projection being bent down behind the finger piece to prevent its return to the wide portion of the slot and any longitudinal movement of the detent.

Signed at North Attleboro, Massachusetts, this third day of February, 1927.

CHARLES H. BATCHELDER.
